UNITED STATES PATENT OFFICE

163,764

HOUSING FOR FLUID DISPENSING
APPARATUS

Peter Muller-Munk, Pittsburgh, Pa., assignor to
The Wayne Pump Company, Fort Wayne, Ind.,
a corporation of Indiana

Application November 30, 1950, Serial No. 13,196

Term of patent 14 years

(Cl. D52—2)

To all whom it may concern:

Be it known that I, Peter Muller-Munk, a citizen of the United States, residing at Pittsburgh, in the county of Allegheny and State of Pennsylvania, have invented a new, original, and ornamental Design for a Housing for Fluid Dispensing Apparatus, of which the following is a specification, reference being made to the accompanying drawing forming a part thereof.

In the drawing—

Figure 1 is a perspective view of a housing for fluid dispensing apparatus as seen from the dispensing side, showing my new design.

Figure 2 is a perspective view of the housing apparatus as seen from the side opposite to the dispensing side; and

Figure 3 is a plan view of the housing.

The essential features of the design reside in the solid line portions.

I claim:

The ornamental design for a housing for fluid dispensing apparatus, substantially as shown and described.

PETER MULLER-MUNK.
